CLAIM

The ornamental design for a brass bed bracket, as shown and described.

DESCRIPTION

FIG. 1 is a right side elevational view of a brass bed bracket showing my new design, the side opposite thereof being a mirror image;

FIG. 2 is a front, top and right side perspective view of the first embodiment, the side 180 degrees opposite to this view being a mirror image; and,

FIG. 3 is a front, top and right side perspective view of a second embodiment thereof, the 180 degrees view of the side thereto being a mirror image.

FIG.1.

FIG.2.

FIG.3.
